[57] CLAIM

The ornamental design for a runner trophy, as shown and described.

DESCRIPTION

FIG. 1 is a front elevational view of a runner trophy
showing my new design;

FIG. 2 is a rear elevational view thereof;

FIG. 3 is a top plan view of the figure alone with the square base removed for clarity of illustration; and

FIG. 4 is a bottom plan view thereof.

FIG. 1

FIG. 2

FIG. 4
